UNITED STATES PATENT OFFICE.

MARCUS E. COVINGTON, OF SAN FRANCISCO, CALIFORNIA.

DISPENSING-PACKAGE.

1,192,868.

Specification of Letters Patent.

Patented Aug. 1, 1916.

Application filed April 14, 1914, Serial No. 831,725. Renewed June 20, 1916. Serial No. 104,806.

To all whom it may concern:

Be it known that I, MARCUS E. COVINGTON, a citizen of the United States, residing at San Francisco, in the county of San Francisco and State of California, have invented a new and useful Dispensing-Package, of which the following is a specification.

This invention relates to a package adapted for holding products which are contained in collapsible tubes, and the object of the invention is to provide a casing for the collapsible tube, which will protect the tube, and which can stand erect upon a shelf or table.

15 A further object is to provide means accessible externally of the casing for collapsing the tube to expel the contents in the amount desired.

The ordinary collapsible tube is unsightly, particularly when partially collapsed, with its sides dented in, and moreover, it cannot be stood erect, but has to lie flat, and it must be handled with care or the tube will become pinched and expel the contents when not needed if the cap is not screwed in position. All of these disadvantages of the collapsible tube are overcome with the present invention, and it may be handled with impunity even if the cap is unscrewed, and may be carried 25 in traveling packed among other toilet articles without danger of being squeezed and losing the contents. The package is thus adapted for tooth paste, shaving cream, cold cream, ointments, and other toilet preparations. While of especial advantage for such products, the package is also adapted for any product which may be dispensed from a collapsible tube, for example, certain food products, such as mustard, may be prepared 35 of the proper consistency and packed in the tube, and the package may be placed on the table, and being covered, the mustard will keep for a much longer time than where it is kept in an open receptacle.

45 The device is so constructed that the collapsible tube may be removed from the outer package and a fresh tube substituted, which construction enables the outer case to be formed of silver or other valuable ornamental design, although the outer case may be constructed of very cheap metal and may be thrown away with the collapsible tube when the latter is empty.

Another object is to provide a construction 55 that will prevent twisting of the collapsible tube when the cap is turned, thus insuring

against binding of the key against the margins of the slot of the case through which the key extends.

Referring to the drawings: Figure 1 is a 60 side elevation of the device, with the thumb piece folded against the case to enable closely packing the packages. Fig. 2 is a side elevation. Fig. 3 is a vertical section on line x^3-x^3 , Fig. 2, showing the collapsible tube 65 partly collapsed, and dotted lines showing it nearly entirely collapsed.

The device comprises an external case 1, which may be of any preferred form, with a bottom 2 and a removable top 3, the top 3 70 being sufficiently tight on the case 1 to prevent accidental displacement. The case 1 has a longitudinal slot 4 in one side thereof. Within the case is a collapsible tube 5 of ordinary construction with a key 6 at its lower 75 end with folding thumb piece 7, which projects through the slot 4, and is accessible externally of the case, so that by turning the thumb piece 7, the lower end of the tube 5 may be rolled up to expel the contents. The 80 nozzle 8 of the tube 5 projects through the cover 3 and screwed thereon is a hollow nut 9, which serves as an outer nozzle, and also as a means of rigidly fastening the tube 5 to the cover so that the tube 5 is firmly held 85 in proper position within the case 1. A screw cap 10 is provided for the nozzle 9. By removing the cap 10 and winding up the thumb piece 7, the collapsible tube may be rolled up from its lower end, which will expel 90 the contents through the nozzle 9. In packing the device the thumb piece 7 may be folded against the case 1, as shown in Fig. 1.

It is noted that by providing a screw-threaded nozzle 8 projecting through the top 95 3 and having the tube 5 seat against the inside face of said top, and providing an external nozzle 9 screwed to the tube nozzle and seated against the outside face of said top, the collapsible tube will be firmly held 100 against turning when the cap 10 is turned.

It is essential in a device of this character that the tube be held firmly against movement relative to the case, for if the nozzle end of the tube should be twisted 105 relative to the key end, the operation of the key when said key is wound sufficiently to bring it to the nozzle end of the tube would be difficult and would not express the contents of the tube therefrom satisfactorily.

Devices in general of this character have been invented heretofore but in them there

has been no provision for positively holding the tube against becoming twisted and disarranged, and I have made provision for thus holding the tube firmly relative to the case so that the tube will not become twisted and cause the key to bind against the case and thus interfere with the turning thereof when rolling up the tube.

What I claim is:

- 10 The combination with a case having a removable top formed with the opening centrally therethrough, of a collapsible tube mounted in the case and having a screw threaded nozzle thereon extending through the opening in the top, said tube seated against the inner face of the top, means op-
- 15

erable externally of the case for rolling up the tube to expel the contents thereof, an external nozzle having its bore at its inner end enlarged and screw threaded to receive 20 the nozzle on the tube, said external nozzle seated upon the outer face of the top and having its end screw threaded externally and a cap turned on the outer end of said last mentioned nozzle.

In testimony whereof, I have hereunto set my hand at Los Angeles, California, this 9th day of April, 1914.

MARCUS E. COVINGTON.
